UNITED STATES PATENT OFFICE.

JACOB B. NEEVEL, OF KANSAS CITY, MISSOURI.

SUPPORTING-TIE FOR ROD.

1,151,378.

Specification of Letters Patent. Patented Aug. 24, 1915.

Application filed April 22, 1915. Serial No. 23,109.

To all whom it may concern:

Be it known that I, JACOB B. NEEVEL, a citizen of the United States, residing at Kansas City, in the county of Jackson and State of Missouri, have invented certain new and useful Improvements in Supporting-Ties for Rods, of which the following is a full, clear, and exact description, such as will enable others skilled in the art to which it appertains to make and use the same.

The invention relates to supports and ties for concrete reinforcing rods and seeks to provide an improved support and tie of simple and efficient form wherein the metal is cut and formed to give increased strength with a less amount of material and no waste of stock, two supports being provided and so arranged that whether the tie be applied to a single rod or crossed rods the rod crossing the tie transversely will always be positioned centrally over the support so that the tie will stand more rigid, the particular shape also leaving the full width of the material midway between the supports which greatly increases the stiffness and supporting strength of the tie.

Supports and ties are necessarily cut from straight bars of metal and owing to the very low price at which they are sold it is very advantageous to so shape the material as to employ the least amount of stock for each tie and yet retain strength and rigidity.

It is essential that the support and tie remain in an upright position while the rods are being applied and afterward and that they possess sufficient strength to sustain immense loads as many wagon loads of reinforcing rods in handling preparatory to placing in the supports and ties are often piled upon the rods that have been placed in the supports and ties ready to receive the concrete. For these reasons the greatest strength with the least amount of material is of great importance.

The present invention seeks to provide an improved support and tie for concrete reinforcing rods that may by bending the arms thereof be secured to single rods or crossed rods securely binding the rod or rods to the tie and supporting means to support the rods in a separated position from the surface to which the support and tie may be secured so that the rods may be embedded in the concrete that may be poured about them.

A further object of the invention is to so shape the support and tie that the greatest

amount of metal will be positioned immediately underneath the point of intersection of crossed rods and immediately underneath the center of the bearing of a single rod when the support and tie is applied to rods on an upward facing surface, whereby the greatest amount of strength is attained with the least amount of metal.

The invention consists in the features of improved construction hereinafter set forth, illustrated in the accompanying drawings and more particularly pointed out in the appended claims.

In the drawings:—Figure 1 is a view in elevation of the reinforcing support and tie applied to crossed rods. Fig. 2 is a view in elevation of the support and tie applied to crossed rods, the view being taken at a horizontal angle of ninety degrees from that of Fig. 1. Fig. 3 is a view in elevation of the support and tie applied to a single rod. Fig. 4 is an inverted plan view of the support and tie showing but one rod. Fig. 5 is a view of the sheet metal as it is cut from the bar of stock and before it is bent to form a support and tie.

The plate 1 of sheet metal represents the material cut to the required shape before being bent to form the support and tie, the end 2, 3, 4, 5 and 6 having been cut from a companion tie having the same shape as end 7, 8, 9, 10 and 11 with no waste of material, the slits 12 and 13 being cut at the same operation, and the lines 14, 15, and 17 indicating the location of the bends that form the support and tie of the plate.

The supporting table 18 is approximately a plane surface the sides 19 and 20 thereof extending to the full width of the outside width over the arms 21, the arms being spaced apart to receive rods longitudinally of the table as rod 22 and standing upward at right angle from the table as dotted lines 21^a before the tie is applied, the arms being bent to grip the bar or bars tightly against the table when applied as shown in Figs. 1, 2 and 3.

Each of the ends 23 and 24 of the table extend approximately the same distance in opposite direction and are of a width equal to the distance between the arms 21, the supports 25 and 26 leading downward respectively from the ends 23 and 24 of the table for the purpose of supporting rods at the desired elevation from the surface on which the supports rest.

The nail 27 is shown in Fig. 1 securing the support and tie to the fragmentary structure 28 but this feature is subject matter of claims in my copending application Serial No. 20,936 and is not claimed herein.

5 It will be noticed that the rod 29 of crossed rods as well as the rod 30 of a single rod application lies approximately transversely of the table 18 and approximately in the center of the length of the table, also that the table at this point as indicated by the location of the ends 19 and 20 is as wide as the greatest width of the support and tie, the same being equal to the width over the 10 arms 21, the table portion of the support and tie being so shaped for the purpose of strengthening the central portion thereof, which is well known to be the ordinary weak point owing to the concentration of 15 weight.

20 The location of the arms 21 to position the bar 29 and the bar 30 centrally with reference to the length of the table 18 has the further advantage of placing equal weight 25 on each of the supports 25 and 26 and lessens the liability of their cutting into the wood of the structure to which they are applied, also the support and tie will stand very much more rigid and have less inclination to tip over which is also very 30 advantageous.

By bending the arms from the end portions of the metal and leaving the table 18 the full width thereof a thinner metal may 35 be used than would otherwise be required were the arms cut and bent from the central portion of the table and a thinner metal results in the lowering of the cost of the

material to produce one or any given number of the support and ties.

What I claim as new, and desire to secure by Letters Patent, is:—

1. In means for securing and supporting concrete reinforcing rods, the combination of a supporting table, a pair of arms rising from said table intermediate one end and the center thereof, each end of said table having the width of the distance between said arms, and the central portion of said table being equal to the outside width of said arms.

15 2. In means for securing and supporting concrete reinforcing rods, the combination of a supporting table, a pair of arms rising from said table intermediate one end of and the center of said table, each end of said table having the width of the distance between said arms, the central portion of said table being equal in width to the outside width of said arms, and a support extending 55 from each end of said table.

3. The combination of a table, said table being wide at the center of the length thereof, said table being of a lesser width at each end than at the center of the length 60 thereof, a support projecting from each end of said table, and arms projecting from said table by which reinforcing rods may be secured thereto.

65 In testimony whereof I affix my signature in the presence of two witnesses.

JACOB B. NEEVEL.
